United States Patent Office

Des. 231,713
Patented May 28, 1974

231,713

MAIL BOX OR SIMILAR ARTICLE

Duane H. Nesbitt, 2817 E. Serendipity Circle, Colorado
Springs, Colo. 80917, and Jimmy P. Hayes, Colorado
Springs, Colo.; said Hayes assignor to said Nesbitt

Filed Aug. 27, 1971, Ser. No. 175,793

Term of patent 14 years

Int. Cl. D31—00

U.S. Cl. D74—9 R

Fig. 1

Fig. 2

Fig. 3

Fig. 4

FIG. 1 is a right side elevational view of a mail box or similar article showing my new design. The side not shown is a mirror image of the side shown with the exception of the signal flag assembly.

FIG. 2 is a front elevational view.

FIG. 3 is a top plan view.

FIG. 4 is a rear elevational view.

We claim:

The ornamental design for a mail box or similar article, as shown and described.
